UNITED STATES PATENT OFFICE.

JOSEPH H. SAUTER, OF NEW YORK, N. Y.

WASHING MACHINE.

1,427,552.

Specification of Letters Patent. Patented Aug. 29, 1922.

Application filed October 17, 1921. Serial No. 508,294.

To all whom it may concern:

Be it known that I, JOSEPH H. SAUTER, a citizen of the United States, residing at New York, in the county of Kings and 5 State of New York, have invented certain new and useful Improvements in Washing Machines, of which the following is a specification.

This invention relates to washing machines and has particular reference to an attachment which can be secured to the usual type of tub used for the washing of clothes, and has for its main object the provision of a machine which, will vigorously 10 agitate the washing liquid throughout, so that any articles in the same will have its fabric thoroughly cleansed by the seepage action of the liquid, induced by the agitation.

Another object is to provide a machine 15 having a series of splashes which will beat the surface of the liquid thereby inducing the soapy solution into a foam, in which state it is a very active agent for the cleansing.

Still another object is to provide a machine which can be quickly inserted and secured in a wash tub, so designed that 20 changeability of parts with respect to the motor can be had, this being desirable when the coarse fabric of working garments and 25 the much finer texture of silks is considered.

A still further object of splashes is to beat down into the liquid any of the clothes which may force themselves above the 30 surface.

The above and other objects will become 35 apparent in the description below in which characters of reference will refer to the like-named parts in the drawings.

Referring briefly to the drawings, Figure 40 1 represents a cross-sectional, side elevation of the wash tub with the washing machine attachment mounted therein, the section being taken on line 1—1 of Figure 2.

Figure 2 is a top plan view of the same 45 showing the cover plate in place and the means for rotating the device mounted on the cover.

Figure 3 is a top plan view of the washer 50 spindle with all the parts attached thereto.

Figure 4 is a perspective view of the 55 splasher carrier.

Figure 5 is a perspective view of the liquid agitator.

Referring in detail to the drawings the 55 numeral 10 indicates the bottom of a com-

mon rectangular set-tub having ends 11, rear side 12 and the outwardly inclined front side 13 forming a conventional tub into which the water is placed and the clothes 60 to be washed immersed therein.

A board 14 having corrugations 15 formed on its upper surface covers the entire tub bottom 10. The corners of the board 14 have the uprights 16 secured thereto the 65 latter forming rests for the wooden frame 17 which snugly fits the open top of the tub.

A T-shaped frame 18, secured to the top surface of the frame 17, serves as a reinforcing member for the cover, which carries 70 the whole washing attachment.

Bearing brackets 19 secured to the reinforcing plate 18, revolvably receive a horizontally disposed shaft 20, to the one end of which a beveled gear 21 is secured. The opposite end of the shaft 20 has a crank 24 fixedly secured to it both being rotated by 75 grasping the handle 25.

A beveled pinion 22 in mesh with gear 21, and secured to the vertical spindle is revolvably fixed to the frame of the tub, the spindle 80 23 passing into the tub chamber.

A carrier bar 28 has a central flange 27 the latter having an integral sleeve 26 with a hole 26' to slidably receive the spindle 85 23, and it can be adjustably secured in any desired position on the spindle by the thumb nut 29. Inclined surfaces 30, formed on the carrier bar 28, slope in opposite directions with respect to each other and have a pair 90 of splashes 31 secured to each end by screws. The splashes are close to the surface of the water and are adapted to beat down any clothes which may work themselves above the surface. 95

A vertically disposed agitator 32 is releasably secured to the carrier bar by a pin 100 engaging holes 34 in plates 33, the latter being secured to opposite sides of the agitator 32, and a hole 34' located in the carrier.

Flexible rubber wings 35, in planes tangential to the center of member 32 and somewhat off-set from it, extend outwardly from the member 32 and are secured to it by the angular members 36 through the medium of rivets. 105

The base agitator 32 has a hole 37 which engages the pin 38 fixed in the corrugated board bottom 14 and forms an end pivot bearing for the agitator. 110

From the drawing and foregoing description it is apparent, that by grasping shaft

20 the entire washing attachment can be lifted clear of the tub, after the thumb-screws 38 have been withdrawn.

In order to fill the wash tub with clothes 5 the entire rotor is detached from the spindle 23 by releasing the screw 29, after which the rotor is centered by engaging the stud 38.

Then, the tub is filled with a washing fluid extreme nearly to the ends of the 10 splashers 31.

In operation, clothes are thrown into the tub through openings provided in the cover frame 17. The tub is then filled until the 15 fluid surface is in imminent contact with the ends of splashers 31, after which washing is accomplished by rotating the crank handle 25.

When the device is not in use it can be 20 easily detached by withdrawing the thumb screws 38, after which the reinforcing plate and all the members mounted thereon can be freed from the cover 17 and conveniently stored within the tub, thereby permitting covering the entire tub without having to 25 guard against any projections.

I claim:

1. A washing machine comprising the combination with a tub having a corrugated bottom, of a frame removably engaged in 30 said tub, a cylindrical element rotatable on a vertical axis in the tub, flexible vanes extending lengthwise of said element in opposed lateral relation, a bar extending transversely across the top of said element, 35 a spindle engaging said bar axially of said element, said spindle being rotatably guided in one of the frame members, a pintle on the

lower end of said cylindrical element, said pintle resting in the bottom of the tub, and means for manually rotating said spindle. 40

2. A washing machine comprising the combination with a stationary tub, of a corrugated false bottom, a frame suited to the interior walls engaging said corrugated bottom, a cylinder rotatably mounted in a 45 vertical plane in said tub, a pair of oppositely disposed flexible vanes fixed on said cylinder to extend outwardly at both ends, a bar having oppositely inclined seats, beaded elements fixed on said seats, and means for rotating said cylinder and bar. 50

3. The combination with a fixed rectangular wash-tub of a washer comprising a bottom plate and frame members, the upper-most of said frame members having bearing brackets, a shaft revolvably mounted, a shaft, said shaft having a crank arm at one end and a beveled gear at the opposite end, a beveled pinion secured to a vertical spindle and in mesh with said gear, a cross bar having a collar attached to the upper surface thereof, said collar slidably engaging the spindle, inclined surfaces on the cross bar disposed in opposite directions to each other, a pair of splasher mounted on each of the inclined surfaces to extend outwardly from said cross bar in opposite directions an agitator attached to the cross bar and flexible elements having straight unbroken edges disposed vertically on said 60 agitator. 65

In witness whereof I, affix my signature.

JOSEPH H. SAUTER.
